COMBINED LADDER AND SUPPORT HOLDER THEREFOR

Keith David Bernkramt, Miami, Fla., assignor to
Firearms Import & Export Corp.

Filed Feb. 9, 1976, Ser. No. 656,300

Term of patent 14 years

Int. Cl. D6—99

U.S. Cl. D25—64

FIG. 2

FIG. 5

FIG. 3

FIG. 1

FIG. 4

FIG. 1 is a side elevational view of a combined ladder and support holder therefor showing my new design;

FIG. 2 is a front elevational view thereof;

FIG. 3 is a top plan view thereof;

FIG. 4 is an enlarged fragmentary sectional view taken along line 4—4 of FIG. 3; and

FIG. 5 is an enlarged perspective view of the support holder, it being understood that the pipe ladder has been omitted for convenience of illustration.

The characteristic feature of my design resides in the arrangement of separate coupling members adjacent the upper and lower surfaces of each step and the pattern of vertically spaced grid works formed by the vertical members at the ends of each step as best illustrated in FIG. 1.

I claim:

The ornamental design for a combined ladder and support holder therefor, as shown and described.
